UNITED STATES PATENT OFFICE.

DANIEL BEVIS, OF MARION, OHIO.

CAR-COUPING.

SPECIFICATION forming part of Letters Patent No. 251,760, dated January 3, 1882.

Application filed September 28, 1881. (No model.)

To all whom it may concern:

Be it known that I, DANIEL BEVIS, a citizen of the United States of America, residing at Marion, in the county of Marion and State of Ohio, have invented certain new and useful Improvements in Car-Couplings; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

The object of this invention is to provide a simple and convenient arrangement of devices for coupling and uncoupling cars, in which the bumpers are of a different height, and without the necessity of passing between the cars.

To this end the invention consists in the construction and combination of devices, as hereinafter more fully described and claimed.

In the annexed drawings, which fully illustrate my invention, Figure 1 is a top or plan view of my improved coupling. Fig. 2 is a longitudinal section of the same on the line $x-x$, Fig. 1. Fig. 3 is a front view, and Fig. 4 is a section on the line $y-y$ of Fig. 3.

Like letters indicate like parts in the several views.

30 A represents the end of a car, to which are attached suitable ways, $a a'$, for the support of the sliding draw-head or bumper B, which is recessed at the sides for the engagement therewith of the lateral guideways a , that fit in the slots or recesses b .

Above the sliding bumper B, and secured to the end of the car, is a bracket, C, that supports a metal frame, D, the top of which consists of a frame-work of bars, D', which extend 40 outwardly toward each side of the car. At each end of the upper frame-work, D', is a standard, E, in which is pivoted a lever, F. These levers F F are bent downward, and are slightly curved at their inner ends for engagement with openings c formed in lugs $d d$, that are attached to a box or framing, G, the lower end of which is open, while its sides are adapted to move vertically in an opening left at each side or end of the frame D.

50 In the top of the box G is formed an elongated slot, e , for the passage of the coupling-

pin f , which is provided with an enlarged head that is supported by the sides of the slot e , while the pin passes down through a corresponding opening in the bottom of the frame 55 D, and also through a circular opening in the top of the draw-head B, and rests in a circular recess or opening at the bottom of the same. The draw-head and coupling-pin thus have sufficient play to resist the usual tendency to 60 strain.

It will be seen that when the outer end of either lever F is drawn down the box G will be raised, carrying with it the coupling-pin f , so as to permit the entrance or withdrawal of the 65 link g into or from the mouth of the draw-head. The upward movement of the box G, when operated by the levers F F, is limited by means of a pin or stud, i , on each end of the box, which pins come in contact with the under surface of the frame D at its upper part as soon as the coupling-pin has been elevated sufficiently. The box G, when lowered, is supported on vertical studs $p p$, surrounded by spiral springs ss , that normally project slightly 75 above said studs, and thus obviate undue jar when the box is dropped in the act of coupling. By means of either lever F the car may thus be readily coupled or uncoupled from either side without the necessity of passing 80 between the cars.

In order to provide a means for raising the link when the car is to be coupled with another having a draw-head of different height, I provide additional levers, which are so pivoted and arranged as to be capable of movement in any required direction to accomplish the desired result with ease and safety. For this purpose a bracket or bend, h , at each anterior corner of the upper frame, D', supports 85 a swivel, k , in which is pivoted a lever, H, that may be thus brought into position either transversely or longitudinally with relation to the car, or may be swung to any angle necessary to properly support and guide the link 90 into the mouth of the draw-head.

The levers F H are in such proximity to each other as to be readily operated by one person without exposure to danger from passing between the cars while being coupled. 100 These levers are pivoted in their supports or fulcrums by means of removable pins m in such

a manner as to be readily detached when required.

From the foregoing description the operation and advantages of my improved coupling devices will be readily understood.

What I claim as my invention, and desire to secure by Letters Patent, is—

1. The combination, with the draw-head B and frames D D', having standards E E, of the levers F F, pivoted in said standards, and the slotted and spring-seated box or frame G, adapted to move vertically in the frame D D', and having lugs d d for engagement with the inner ends of the operating-levers, substantially as set forth.

2. The combination, with the frame D, having brackets h h, of the swivels k k and levers H H, pivoted therein, whereby said levers may be moved in any desired direction for supporting and guiding the coupling-links, substantially as shown and described.

In testimony whereof I affix my signature in presence of two witnesses.

his
DANIEL X BEVIS.
mark.
